UNITED STATES PATENT OFFICE.

JOHN W. FIELDS, OF SHERMAN, TEXAS.

IMPROVEMENT IN PRESSES.

Specification forming part of Letters Patent No. **147,317**, dated February 10, 1874; application filed November 22, 1873.

To all whom it may concern:

Be it known that I, JOHN W. FIELDS, of Sherman, in the county of Grayson and State of Texas, have invented a new and Improved Press, of which the following is a specification:

The invention will first be fully described, and then pointed out in the claim.

Figure 1 is a horizontal section of my improved press, taken on line *xx* of Fig. 2. Fig. 2 is a vertical section, taken on the line *yy* of Fig. 1; and Fig. 3 is an elevation of the wheel of the sweep, the latter being sectioned on the line *zz*.

Similar letters of reference indicate corresponding parts.

A is the press-case, which is arranged horizontally. B is the follower; C, the follower-stem; D, the guide-pulleys on the stem; E, the ropes or chains; F, the pulley on the sweep *G* for working said chains; H, the point where the chains or ropes are fastened to the

frame of the machine, and J the points where the ropes or chains are fastened to the sweep-pulley.

As the ropes or chains run in opposite directions from the points of connection to the wheel, over the latter, and the guide-pulleys to the point of fastening to the press-frame, it will be seen that a forward-and-backward movement of the sweep will move the follower up and back.

Having thus described my invention, I claim as new and desire to secure by Letters Patent—

The combination, with the press-case A, having shaft H, and follower B, having stem C, of the guide-pulleys D D, rope E, and vibratory sweep-pulley F, having arm G, as and for the purpose described.

JOHN W. FIELDS.
